UNITED STATES PATENT OFFICE.

WILLIAM F. MOON, OF MILWAUKEE, WISCONSIN.

YARN-SPECK REMOVER.

1,336,148.

Specification of Letters Patent.

Patented Apr. 6, 1920.

Application filed November 1, 1919. Serial No. 334,998.

To all whom it may concern:

Be it known that I, WILLIAM F. Moon, a citizen of the United States, and resident of Milwaukee, in the county of Milwaukee and State of Wisconsin, have invented new and useful Improvements in Yarn-Speck Removers, of which the following is a description, reference being had to the accompanying drawings, which are a part of this specification.

The present invention relates to a device for removing lumps of fiber or what are commonly termed "specks" from yarn or thread, previous to its use in a spinning or weaving machine.

One object of this invention is to provide a device of this character which will include movable members for crushing or severing the speck from the thread.

Another object of the present invention is to provide a device of this character which will have movable and yieldable means coöperating with a speck positioning member to crush or sever the speck from the thread or yarn.

With the above and other objects in view which will appear as the description proceeds, my invention resides in the novel construction, combination and arrangement of parts, substantially as hereinafter described and more particularly defined by the appended claims, it being understood that such changes in the precise embodiment of the herein disclosed invention may be made as come within the scope of the claims.

In the accompanying drawings I have illustrated two complete examples of the physical embodiment of my invention constructed according to the best modes I have so far devised for the practical application of the principles thereof, and in which:

Figure 1 is a side view of one form of my invention, parts being broken away and in section to more clearly illustrate the details of construction thereof.

Fig. 2 is a top plan view thereof, parts being broken away and in section to more clearly illustrate structural details.

Fig. 3 is a transverse sectional view taken through Fig. 1 on the line 3-3.

Fig. 4 is a side view of one end of the device, parts being broken away and in section.

Fig. 5 is a side view of a modified construction of a speck remover employing the principles of my invention, said view hav-

ing parts broken away and in section to more clearly illustrate the details of construction.

Fig. 6 is a view, part in section and part in elevation, said view being taken on the line 6-6 of Fig. 5.

Fig. 7 is a side view of a still further modified form of my invention, said view having parts broken away and in section, 65 and

Fig. 8 is a view, part in section and part in elevation, said view being taken on the line 8-8 of Fig. 7.

Referring now to the drawings, and more particularly to Figs. 1 to 4 inclusive, the numeral 10 designates generally the frame of the machine which has a plurality of opposed pairs of upwardly extending arms 11 having apertures 12 in their upper ends, a 75 plurality of opposed pairs of rocking members 13 being medially pivoted to the arms 11 by means of pivots 14 having their inner ends in threaded engagement with the apertures 12 and their shanks providing supporting journals for the members 13, and means being engaged with the lower ends of the members 13 to rock the same on their pivots 14.

In the drawings, I have illustrated a plurality of speck removing devices, each of which successively acts upon the threads to remove any speck thereon, so that if the first device does not remove the speck it will be removed by another of the devices. 90

Each of these speck removing devices is mounted on the adjacent arm 11, and consist generally in means for presenting the speck in a position in which it may readily be severed from the thread or yarn by the 95 crushing members hereinafter described.

The means for presenting the speck in position to either side consists of a bed block 15 secured to the frame 10 by means of a fastening member 16 intermediate each opposed pair of arms 11 as best shown in Fig. 3. The bed block 15 is in the form of a stationary member and coacts with the rocking crushing means, to be later described. The yarn or thread 17 is guided through 100 the frame member 10 by means of suitable guiding members 18 and 19, located at each end of the frame, and the thread, in its passage through the frame engages the top of the bed block, and should the speck be on 105 the under side of the yarn, the same will be turned or positioned to the side, there to

be severed or crushed from the thread, as will be later described. As the bed block 15 is insufficient in itself to properly retain the thread upon its top surface in that the 5 thread would possibly become disengaged therefrom, as will be obvious, I so construct by crushing or severing means as to be constantly contacting with the bed block to provide what may be termed a guide channel 10 for the thread as it passes over each bed block. The cutting or crushing means consists of a pair of movable or rocking knife or crushing members 20 having its severing or crushing edge yieldingly held in engagement with the bed block 15, each member 20 being carried by one of the rocking arms 13. As the operation of each adjacent pair of rocking arms 13 and their crushing members 20 is identical, but one 15 pair will be described.

20 The rocking arms 13 disposed on one side of the frame 10 are adapted to be rocked by means of a pitman 21 pivotally secured as at 22 to a connecting rod 23 having pivoted thereto as at 24, the lower ends of the rocking arms 13 disposed on one side of the frame 10 whereby all of the arms 13 on one side of the frame will be rocked in unison. The pitman 21 is oscillated by means of an 25 eccentric 25 adapted to be carried by a shaft 26 adapted to be rotated by a pulley 27 connected with any desired source of power.

30 As best shown in Fig. 2, the rocking arms 13 disposed on the other side of the frame 10 are also connected in a like manner by means of a connecting rod 23 and a pitman 21. As best shown in Fig. 4, the eccentrics 25 are so positioned on the shaft 26 as to insure the pivotally rocking of the arms 13 of each 35 pair whereby a continuous shearing or crushing movement is effected.

35 The upper end of each rocking arm 13 is formed with a cylinder or centrally apertured cap 28, in which is slidably mounted a hollow sleeve end 29 of a retaining block 30. The retaining block 30 is urged downwardly or outwardly of the cylinder 28 by means of an extensile spring 31 disposed in the central bore of the sleeve 29 and having its upper 40 end impinged against a plate 32 engaging the lower end of a tension adjusting screw 33. One of the rocking crushing knife members 20 is secured to the inner face of each retainer 30 by means of a screw 34 and has 45 its lower end yieldingly held in engagement by means of the spring 31 with the adjacent bed block 15.

50 The pivot 14 of each arm 13 has its center in alinement with the top surface of the adjacent bed block 15 to insure the constant engagement of the knife 20 connected therewith with the bed block when the member 13 is rocked. As before described, the crushing knife members 20 of each opposed pair 55 of rocking members are oppositely rocked

and a continuous cutting action is had. The arm 17 is guided through the frame 10 by the guiding members 18 and 19 and passes between crushing members 20 of each pair, which are spaced apart exactly the thickness 70 of the thread and of the bed block 15, the speck, if on the underside of the thread, will be moved or positioned to one side and there severed or crushed by means of the members 20 when they are rocked. 75

Referring now more particularly to Figs. 5 and 6, I employ the same principles as hereinbefore described by using a plurality of pairs of opposed stationary arms 35 somewhat similar in construction to the rocking members 13 with the exception that they are rigid with the frame 10 and in place of the crushing members 20 I employ crushing wheels 36 secured to the retainers 30 by means of a pivot 37 which permits the crushing members 36 to have a free idling movement. In this form of my invention the bed block 15 is in the form of a roll 38 journaled in the frame 10 as at 39 and having a gear 40 mounted on one end thereof which is in mesh with a worm gear 41 fixed to a shaft 42, journaled at one side of the frame 10 and having a gear connection 43 with the shaft 26. 85

90 In this form of my invention the bed block rotates and the knife or crushing members 36 are resiliently urged to engagement therewith by means of the springs 31 and the operation thereof is substantially identical with that of the form of my invention 95 hereinbefore described.

95 Referring now more particularly to Figs. 7 and 8 the frame member 10 has a plurality of parts of alined shafts 44 having their ends in geared connection with shafts 45 100 journaled to either side of the frame 10 and in gear connection 43 with the shaft 26. 105

110 Each shaft 44 has a crushing wheel or knife member 46 fixed to its inner end and engaging an idling roll or bed block 47 journaled in a sliding block or retainer 48 resiliently urged upwardly by means of a spring 49, the spring 49 having a tensioning screw 50 whereby the tension of the engagement of the bed block 47 with the crushing wheels 46 may be regulated. 115

120 The crushing wheels 46 of each pair are spaced apart exactly the diameter of the yarn and the operation of this form of my invention is identical with the form of my invention hereinbefore described.

125 From the foregoing description taken in connection with the accompanying drawings, it will be at once apparent that I provide means for positively cleaning or removing specks from yarn prior to its use in a spinning or weaving machine.

130 What I claim for my invention is:

1. A yarn speck remover comprising means for guiding yarn continuously in a

given direction, and crushing means operable upon the continuously moving yarn for removing specks therefrom.

5 2. In a yarn speck remover, the combination of a bed block, means for guiding yarn continuously over the bed block, and a rockable member coöperating with the bed block for removing specks from the continuously moving yarn.

10 3. In a yarn speck remover, the combination of means for guiding a thread, a bed block for positioning the speck, and a pair of oppositely rocking members for severing the speck from the thread.

15 4. In a yarn speck remover, the combination of means for guiding a thread, a bed block, and movable members yieldingly held in engagement with the bed block, said movable members co-acting with the bed block 20 to crush the speck from the thread as it is guided therethrough.

25 5. In a yarn speck remover, the combination of means for guiding a thread, a plurality of bed blocks adapted to turn the thread to bring a speck thereon to either side, and a plurality of oppositely rocking members yieldingly held in engagement with the bed blocks and co-acting therewith

to crush the speck from the thread as it is guided therethrough.

30

6. In a yarn speck remover, the combination of means for guiding a thread, a fixed bed block, a pivoted arm, means for rocking the arm on its pivot, and a crushing member carried by the pivoted arm and co-acting 35 with the bed block to crush the speck from the thread as it is guided therethrough.

7. In a yarn speck remover, the combination of means for guiding a thread, a fixed bed block, a pivoted arm, means for rocking 40 the arm and yieldingly held in engagement with the bed block to crush the speck from the thread when it is rocked on the bed block by means of the arm being rocked on its pivot.

45

8. In a yarn speck remover, the combination of means for guiding a thread, a plurality of bed blocks over which the thread is guided, and pairs of movable members operable upon the bed blocks and providing 50 thread passageways, said members co-operating with the bed blocks to sever specks from the thread as it is guided through said passageways.

In testimony whereof, I affix my signature. 55
WILLIAM F. MOON.
